UNITED STATES PATENT OFFICE.

ARTHUR GIESLER, OF DAYTON, OHIO.

TURBINE-WATER-WHEEL CONSTRUCTION.

No. 814,002.

Specification of Letters Patent.

Patented Feb. 27, 1906.

Application filed May 31, 1905. Serial No. 263,076.

To all whom it may concern:

Be it known that I, ARTHUR GIESLER, a citizen of the United States, residing at Dayton, in the county of Montgomery and State 5 of Ohio, have invented certain new and useful Improvements in Turbine-Water-Wheel Constructions; and I do declare the following to be a full, clear, and exact description of the invention, such as will enable others 10 skilled in the art to which it appertains to make and use the same, reference being had to the accompanying drawing, and to the letters of reference marked thereon, which forms a part of this specification.

15 This invention relates to improvements in turbine water-wheels of the horizontal type, either single or duplex.

Heretofore in designing water-wheels it has been the custom to locate on the inside of 20 the flume or housing the dome-cylinder, which is the part of the water-wheel system that excludes the water from the gate and the upper part of the wheel. This manner of locating the dome-cylinder has disadvantages that are well known to those familiar 25 with the construction and installation of water-wheel systems. For example, a flume or housing having the dome-cylinder located on the inside must necessarily be of a length corresponding to the length of the dome-cylinder, including the crown-plate, and according 30 to the number of domes employed. In other words, when the dome-cylinder is located on the inside of the flume or wheel-housing the latter must necessarily be much longer than 35 in the present case, owing to the necessity of providing space on the interior of the flume or housing for the location of said dome-cylinder. In the present case the flume or 40 wheel-housing need not be lengthened on account of the dome or domes, and, further, a more compact construction is obtainable by placing the dome or domes on the outside of the wheel-casing, as will hereinafter appear.

45 The present invention also obviates other disadvantages heretofore existing in water-wheel construction not particularly mentioned above.

To the foregoing ends the present invention consists in a construction and design 50 which enables the dome cylinder or cylinders to be located on the outside of the flume or wheel-housing, where is enabled a convenient access to the water-wheel or runner and the

gate with the least possible disarrangement 55 of the parts, and, further, by thus locating the dome cylinder or cylinders on the outside of the wheel-housing the cost of construction is very materially lessened.

Preceding a detail description of the invention reference is made to the accompanying drawing, which is a vertical longitudinal section of water-wheel mechanism constructed in accordance with my invention.

In a detail description of the invention similar reference characters indicate corresponding parts.

The drawing illustrates a duplex water-wheel system in which the water-wheels or runners A are located upon a single shaft A', 70 provided with suitable bearings.

B designates a dome-cylinder, of which in the present instance there is one located at each end of the flume or wheel-housing C and which are rigidly secured on the outside of 75 said ends. Secured to each of the dome-cylinders is a crown-plate D, which supports end bearings E for the wheel-shaft.

F designates a water-wheel gate within 80 chute-case G, the latter being fixed to the interior of the water-wheel housing, as heretofore. The lower portion of said chute-case has an outward horizontal extension G', that reaches into the lower portion of the dome-cylinder B and supports the gate in a correct 85 position and prevents said gate from tipping over when entirely open. This extension G' is of a rounded or semicylindrical form and, as before stated, is a continuation of the chute-case, being either cast integrally with 90 the chute-case or bolted thereto. The gate, as shown in the drawing, is closed. When open, the extension G' supports it in a true horizontal position.

The dome-cylinders are kept free from water by drain-pipe H, which discharges into the draft-tube I.

Having described my invention, I claim—

1. In a water-wheel system, a chute-case 100 conducting the water to the wheel, a gate within said chute-case, and an extension on said chute-case reaching outwardly into the dome-cylinder, said extension being in alinement with and adapted to receive the gate when opened.

2. In a water-wheel system, a flume, a water-wheel runner housed within said flume, a chute-case within said flume, a gate within

said chute-case, and a dome-cylinder connected directly to said flume on the outside thereof and into which the gate is adapted to move, and means projected outwardly from the chute-case into said dome for supporting the gate when moving into the dome-cylinder, substantially as specified.

In testimony whereof I affix my signature in presence of two witnesses.

ARTHUR GIESLER.
